UNITED STATES PATENT OFFICE.

READ HOLLIDAY, OF HUDDERSFIELD, ENGLAND, ASSIGNOR TO THE READ HOLLIDAY & SONS, LIMITED, OF SAME PLACE.

ACETYLENE-GAS-GENERATING LAMP.

SPECIFICATION forming part of Letters Patent No. 632,117, dated August 29, 1899.

Application filed July 18, 1898. Serial No. 686,315. (No model.)

To all whom it may concern:

Be it known that I, READ HOLLIDAY, a citizen of England, residing at Edgerton, Huddersfield, in the county of York, England, have invented new and useful Improvements 5 in Lamps or Apparatus for Use in Burning Acetylene Gas, (for which I have obtained Letters Patent in Great Britain January 26, 1898, No. 2,078; in Germany June 4, 1898; in 10 France June 7, 1898, and in Belgium June 8, 1898,) of which the following is a specification.

These improvements relate to lamps or apparatus for use in generating and burning acetylene gas produced in the lamps by the 15 action of water on calcium carbide or a similar body, and consist in bringing the water into contact with the carbide by the use of a capillary siphon—that is to say, water is conducted by means of a wick or capillary action 20 to a higher level than the carbide, and by the continuation of the same or another wick or capillary conveyer attached to it the water is drawn downward into contact with the carbide. The descending wick can be opened out 25 and distributed over or among the carbide so as to secure the best and most even production of the gas, the supply of water being stopped or regulated by a valve at one end of a tube, which preferably is that which 30 serves as wick-holder for the ascending water.

Figure 1 is a substantially central vertical section through the lamp. Fig. 2 is a plan of the middle portion of the lamp with the cover removed.

35 A is the carbide-chamber.

B is the reservoir for water, formed by the outer water-tight wall B' and the inner wall B'', leaving the carbide-chamber A referred to within the inner wall and completely isolated 40 from the water in the space between those walls, except by means of the vertical passage afforded by the tube B³ between the two. This tube is filled by a capillary siphon, consisting of a wick C, which has contact with 45 the water and passes up to and down into contact with the carbide in the chamber A. The tube B³ is formed at the top end with a seating B⁴ for a valve D, mounted on a screwed stem D', which engages a correspondingly 50 threaded screw-opening in top of the cover E and is furnished with a milled head D².

When this valve D is screwed down by turning the button D² tightly onto its seat on tube B⁴, the flow of water, which is the natural capillary suction, is checked or entirely stopped, 55 dependent upon the tightness of the junction of those two surfaces with the wick fibers pinched between.

The cover E is connected to the body of the lamp at e by a hinge and at e' by a forked 60 projection, which projection receives between its arms the screw-stem b', hinged at b² to the outer wall of the lamp. This screw-stem b' is locked to the fork e by the screwed button b⁸, while for opening the cover in order to gain 65 access to the internal parts of the lamp the button is loosened and the screw-stem carrying it is swung clear thereof. The cover E is formed with an annular recess, in which is held an annular ring of india-rubber or other 70 suitable packing material, which ring when the cover is pressed into closed position forms a tight packing between those parts.

The L-shaped tube G serves to convey the 75 gas generated in chamber A to the burner H, said burner being socketed in the junction-piece G', connecting the pipe G thereto.

G² is a screw-stopper to open or close the 80 outlet G³ in the junction-piece G' to let out any liquid.

B⁵ is a screw tubular passage communicating 85 between the water-chamber B and the outer air, and into this tube fits the nipple B⁶, the fine opening in which serves as an outlet to relieve any pressure in such chamber.

I is a supporting device for the lamp-body to the bracket of the "machine;" but any other usual or suitable device for the purpose may be employed to effect its support.

J is the burner-chamber, which is here 90 shown provided with a hinged lid or cover J'. Between the burner-chamber in rear of the burner and the adjoining wall of the water-chamber B is interposed an insulating layer of asbestos j, through which and the respective thicknesses of metal B and J the rivets j' j' pass.

J² is an outlet for the products of combustion, and J³ is an asbestos shield provided to shield the same.

J⁴ is the lens in the cover J'.

By these means it will be seen that the feed

of water is attained by the controlled use of the capillary action of the cellular tissue of a fibrous material or wick whereby the water is raised in uniform and easily-regulated 5 quantities from the water-reservoir and deposited on and among the carbid or gas-producing material of a similar nature instead of by utilizing the flow of liquid under pressure with its attendant difficulties of regulation 10 and wastefulness.

Having now particularly described and ascertained the nature of my said invention and in what manner the same is to be performed, I declare that what I claim is—

15 1. In a lamp for burning acetylene gas, the combination with a relatively-fixed carbid-chamber, of a water-chamber surrounding the same, a vertical feed-passage through the carbid-chamber and communicating at the 20 lower end with the water-chamber, a connection having capillary attraction extending through said passage and down into the carbid-chamber, an adjustable pressure-check mounted centrally over said passage and arranged 25 to bear upon said connection at the

point where it is bent over the end of the passage and press the same down against the upper end of the passage through the carbid-chamber, as set forth.

2. In a lamp for burning acetylene gas, the 30 combination with a stationary carbid-chamber and a water-chamber surrounding the same and extending therebeneath, of a tube extending centrally through the carbid-chamber and communicating at the lower end with 35 the water-chamber, a valve seating on the upper end of said tube, a connection between the water and carbid-chambers extending up through the said tube and having capillary attraction and bent over the said seating, and a 40 pressure-check independent of the chambers and adjustable vertically in line with said central tube to press upon the said connection at the point where it bends over the said seating, as and for the purpose specified.

READ HOLLIDAY.
